UNITED STATES PATENT OFFICE

SIDNEY H. SHORT, OF CLEVELAND, OHIO.

TROLLEY FOR ELECTRIC RAILWAYS.

SPECIFICATION forming part of Letters Patent No. 604,196, dated May 17, 1898.

Application filed September 26, 1896. Serial No. 607,111. (No model.)

To all whom it may concern:

Be it known that I, SIDNEY H. SHORT, a citizen of the United States, residing at Cleveland, in the county of Cuyahoga and State of Ohio, have invented certain new and useful Improvements in Electric Railways; and I do hereby declare the following to be a full, clear, and exact description of the invention, such as will enable others skilled in the art to which it appertains to make and use the same.

My invention relates to improvements in electric railways having an overhead conductor, a motor-car, and an underrunning trolley device carried by the car.

Heretofore it has been customary to mount the trolley-arm upon a car by a universal joint or its equivalent, which permits the trolley-arm to move freely both laterally and vertically. The device for engaging with the overhead conductor is mounted in the upper end of the trolley-arm, and the form of such device which has been almost universally used is a sheave or wheel having side flanges.

Every trolley which has had free lateral movement has of necessity had a flanged contact device, and it may also be said that every flanged contact device has necessarily been mounted on a trolley-pole having free lateral motion. The two features of construction have been and are mutually dependent upon each other, and their joint purpose has been to maintain the contact with the conductor however much the said conductor might vary from its intended central position or however much the car in its movement, especially on curves, may carry the point at which the trolley device is supported to one side or the other of the conductor.

The use of laterally-movable trolley-arms and flanged contact-wheels necessitates the attachment of switching devices to the conductor at points corresponding with switches in the track to automatically guide the trolley onto a branch conductor or to keep it on the main conductor, depending upon which the car was or was not switched from the main tracks.

The employment of the trolley having free lateral movement, the flanged contact-wheel mounted thereon, and the switches in the conductors has been practically successful; but

the use of all three of these features of construction has been essential to that success. There are, however, many objections to the use of these mutually-dependent features of construction, among which may be named the cost of installing and maintaining the conductor-switches, the liability of the trolley to jump off the conductor-wire and catch and break the cross-wires, switches, and pass-overs, the great wear on the conductor-wires and flanged wheels at curves, and the fact that since the flanged wheels are necessarily mounted on an oiled bearing the current sometimes carbonizes the oil, whereupon the sheaves stick and are worn flat and wear out the conductor.

The trolley shown in the drawings and hereinafter described has no lateral motion and does not employ a sheave or other contact device with side flanges, indeed cannot employ a device having flanges which will engage with the conductor-wires. It may and should be used in combination with the conductor-wires having no switches, thereby greatly reducing the cost of installing and maintaining the conductors in operative condition. It does not wear the conductors at curves. It cannot jump off the wires nor catch the cross-wires. In short, it has none of the objectionable features of the older constructions mentioned.

The invention consists in the construction and combination of parts hereinafter described and claimed.

In the drawings, Figure 1 is a perspective view of a motor-car, the trolley device, and overhead conductors. Fig. 2 is a plan view of the tracks at a switch and the corresponding conductors. Fig. 3 is a transverse sectional view of a joint between the main and a branch conductor. Fig. 4 is a side elevation of the trolley in its preferred form and the conductor and top of a car. Fig. 5 is a front view of the upper end of the trolley-arm and roller, the latter being partly in section.

Referring to the parts by letters, A represents the trolley-arm, which is pivoted on a horizontal transverse pivot *a* to the top of the motor-car *E*. A spring *B* is employed which exerts its power to force the free end of the trolley-arm upward to hold the contact-roller *C* against the under side of the overhead con-

ductor-wire G, and the trolley-arm has not while in service any lateral movement relative to the car.

The particular stand J shown in the drawings through which the described connection with the car is effected forms no part of this application and no claim is here made to it. It is sufficient for the complete understanding of the present invention to say that to the part thereof to which the trolley-arm is pivoted has no movement relative to the car while the trolley is in service and that the spring B surrounds a fixed rod b and bears at its front end against a nut or shoulder b' 15 on said rod. A collar b², which is movable on the rod, bears against the other end of the spring, and the collar is connected by links b³ with the lower end of the trolley-arm.

The conductors G are wires suspended by any suitable means above the tracks, and, except on curves, they are placed above a line substantially midway between the two rails. It is not important, however, that the conductor-wire should be accurately placed in the described central position. The connections between the main wires and branch wires and between two main wires crossing each other should be made by malleable castings K or their equivalents, which project as little as possible below the wires, the object being to maintain the contacting lower surface of the conductors at branches and cross-overs as nearly as possible in the same plane as at other places, substantially as shown in Fig. 3.

No switches are necessary in the conductors. Indeed, it is essential to the most efficient working of the trolley that there should be nothing connected with the conductors at any point which extends or projects much below the general lower surface of the conductor-wires.

Another advantage of the use of the described trolley is that a plurality of conductors may be used, all of which will contact with the trolley-roller, a construction which cannot be practically used with trolleys having flanged contacting wheels.

The roller C, which must be long enough to maintain contact with the conductor however much the conductor may vary in position, is preferably tubular. It may be mounted on ball-bearings on a spindle e, which is secured to the fork-arms a' a', thereby decreasing friction to such an extent that the roller is sure to revolve freely at all times. It is not necessary to oil these ball-bearings; but the use of oil here will have little if any injurious effect, because I propose to employ one or more brushes H or their equivalent, bearing against the roller, to take off the current. These brushes are secured to the fork-arms by any suitable means, and they may have any desired construction. By the use of these brushes the current does not pass through the bearing of the roller, as it has heretofore in the trolleys using the flanged wheels.

The roller C must be mounted in the extreme upper ends of the forks, whereby no part of the forks shall project above the upper surface of the roller. If the forks or any arm or piece connected therewith did so project, the described operation would be prevented by such projecting part catching upon the conductors as the roller was moved transversely of and out of contact with the wires. 75

The roller C is subject to the greatest wear at and near its middle, and therefore I propose to make the walls of the roller thicker at the middle than at the end. Fig. 5 shows the best construction for effecting this result. In this construction the roller proper is a true cylinder with walls of equal thickness at all points; but a sleeve c', made of copper, bronze, or other suitable material and having a convex surface, is shrunk, cast, or otherwise secured upon the roller C between its ends. 85

The thickening of the roller-walls near the middle, where most of the wear from the conductor comes, prolongs the life of the roller, and the construction in Fig. 5 is particularly practical, since when the sleeve c' has become worn it may be removed and another sleeve secured upon the roller.

When a car equipped with the described trolley comes to a switch in the track and passes onto one track or the other, the trolley contacts with both the main and branch conductors until they are separated sufficiently, when one wire slips off the end of the roller, said roller remaining in operative contact with the conductor above the tracks on which the car is running. No switches in the conductor are necessary or desirable.

Many variations are permissible in the construction of the several parts of the equipment as described without departure from the invention, which is definitely pointed out in the following claims:

1. In an electric railway, the combination of a motor-car, and an overhead conductor, with a trolley-arm mounted on the car by means which permit the vertical movement but prevent the lateral movement of the upper end of the trolley-arm, a horizontal cylindrical roller mounted on the upper end of said trolley-arm, and a convex sleeve secured upon said roller between its ends, substantially as and for the purpose specified.

2. In an electric railway, an overhead conductor, and a trolley-arm mounted upon a car, combined with a horizontal cylindrical roller mounted upon the upper end of the trolley-arm, a sleeve secured upon said roller between its ends, a rod extending through the roller and the ends of the arm, and ball-bearings placed upon the rod, and fitting in the ends of the roller, substantially as described.

In testimony whereof I affix my signature in presence of two witnesses.

SIDNEY H. SHORT.
